US0D1009796S

(12) **United States Design Patent** (10) Patent No.: **US D1,009,796 S**
(45) Date of Patent: ** Jan. 2, 2024

(54) **WIRELESS PLUG**

(71) Applicant: **Shenzhen King-Serry Electronics Co., Ltd**, Shenzhen (CN)

(72) Inventor: **Shiyong Huang**, Ganzhou (CN)

(73) Assignee: **Shenzhen King-Serry Electronics Co., Ltd**

(**) Term: **15 Years**

(21) Appl. No.: **29/836,100**

(22) Filed: **Apr. 25, 2022**

(51) LOC (14) Cl. **13-03**

(52) U.S. Cl.

USPC **D13/137.1**

(58) **Field of Classification Search**

USPC ... D13/137.1–137.4, 108, 199, 139.1–139.8, D13/138–138.2; D14/240; D10/70

(57) **CLAIM**

The ornamental design for a wireless plug, as shown and described.

DESCRIPTION

FIG. 1 is a first perspective view of a wireless plug showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the wireless plug that form no part of the claimed design.

1 Claim, 8 Drawing Sheets
